UNITED STATES PATENT OFFICE.

LUTHER C. VOORHEES, OF NEW YORK, N. Y.

DESIGN FOR A BUCKLE-FRAME.

SPECIFICATION forming part of Design No. 16,046, dated April 14, 1885.

Application filed January 29, 1885. Term of patent 3½ years.

To all whom it may concern:

Be it known that I, LUTHER C. VOORHEES, of the city, county, and State of New York, have produced a new and original Design for 5 Covered Buckles, whereof the following is a specification, reference being had to the accompanying drawings, which form part of this specification.

My new design relates to those buckles 10 whose frame when viewed flatwise exhibits the form of a parallelogram whose sides and one end are straight and the remaining end is rounded.

In the annexed drawings, Figure 1 shows 15 the frame of the buckle viewed flatwise. Fig. 2 is the same as seen in side view, showing the edge of one of the sides. Fig. 3 is a cross-section of the rounded end or of one of the sides.

20 The new configuration of the buckle-frame consists, first, of the plane form of the frame—that is, as viewed from the edge of one side—which form is that of the double reverse wave-line curve, otherwise known as the “line of beauty,” the same being two united arcs curv- 25 ing in opposite ways; and, second, in the form in cross-section of the frame, in combination

with the wave-line plane form, such cross-section consisting of a curve of one sweep on the back side—that is, that which constitutes the 30 under side of the buckle—combined with two outward curves above or on the upper side, making a scallop. The result of this form in cross-section of the sides and rounded end is to produce a crease all around on the upper 35 side of the buckle-frame, like a line of stitching, while beneath the body or frame is intact and has no such crease.

Having thus described my invention, I claim 40 as new—

The design for a buckle-frame in the form of a parallelogram the plane of which is in the double curve or wave line described, and in cross-section shows a rounded under side or back and a scalloped upper side, thus pro- 45 ducing the appearance of a crease in the upper side, as set forth.

In witness whereof I have hereunto subscribed my name in the presence of two witnesses.

LUTHER C. VOORHEES.
